UNITED STATES PATENT OFFICE.

EMMA A. McCLAFERTY, OF LOS ANGELES, CALIFORNIA.

ADJUSTABLE WASHBOARD SUPPORT.

Application filed April 6, 1926. Serial No. 100,071.

This invention relates to wash board supports whereby a wash board may be held firmly in any desired position as to angularity or side movement when used in the ordinary wash tray or laundry tub.

This invention has for one of its principal objects means for adjusting the angle of the board as it sets in the tub to accommodate persons of different heights, and also to prevent the board from slipping sidewise from pressure exerted by the operator.

Another object of this device is to provide means whereby it may be readily and easily attached to the tub when desired for use and as readily removed when the washing is completed.

These and other objects are attained in the manner illustrated in the accompanying drawing, in which—

Figure 1 is a perspective of the complete device detached from the tub or tray.

Figure 2 is a sectional view of the tub with the wash board support in position, and the wash board shown in full lines in one of its positions and in dotted lines in another position.

Figure 3 is a fragmentary view of the tub, the wash board being shown in its highest adjusted position, the wash board support being shown in dotted lines, with the exception of the supporting ears which are shown in full lines.

Figure 4 is a fragmentary view of the wash board showing the pins which engage the support.

Similar characters of reference design-

nate like parts through the several views.

Referring to Fig. 1, A is the body of the wash board support, B and B' are hooks bent to conform to the upper edge of the tub, the ends b and b' are bent at such an angle that they conform closely to the outside of the tub and the ends of the body are bent forwardly at approximately a right angle, as shown at C and C' and angular open end slots D and D' are formed therein for the reception of the supporting pins f and f' which project from each side of the board, but are only shown upon one side of the fragmentary view Fig. 4.

In operation the device is hooked over the front edge of the tub as shown in Figs. 1 and 3, then the wash board is placed between the hooks C and C' as shown in Fig. 3 and the pins f or f' are dropped down into the slots D and D' according to the height required to suit the operator, when it is ready for use.

Having thus described my invention, what I claim and desire to secure by Letters Patent is—

In a wash board support, a body member provided with means for engaging the top edge of a tub, slotted ears projecting inwardly from said body member, a wash board having pins projecting outwardly from each side of said board and adapted to engage the slots in said ears to hold the board at various predetermined angles to suit the requirements of the user.
